UNITED STATES PATENT OFFICE.

WILLIAM B. SMITH, OF DANVILLE, ILLINOIS.

DOOR-CHECK.

1,127,689.

Specification of Letters Patent.

Patented Feb. 9, 1915.

Application filed January 31, 1914. Serial No. 815,613.

To all whom it may concern:

Be it known that I, WILLIAM B. SMITH, a citizen of the United States, and resident of Danville, in the county of Vermilion and State of Illinois, have invented certain new and useful Improvements in Door-Checks, of which the following is a specification.

My invention relates to door checks or closers and has particular reference to a novel liquid check arranged for swing doors.

In door checks heretofore suggested, much difficulty has been experienced in providing for rigidity, freedom from leakage and ease in opening, with the requisite restraining effect in closing. In liquid checks employing pistons, it is difficult to secure absolute freedom from leakage without employing glands secured so tightly that freedom of operation is interfered with.

20 An object of my invention therefore, is the construction of a liquid door check which is adapted for use without the employment of stem packing, with the result that the operation is unrestrained by friction. This is accomplished by providing a valved chamber above the liquid containing chamber and through which the operating stem projects. Because of the check valve connecting the liquid chamber with the over-flow or escape chamber, no liquid is allowed to escape into the over-flow chamber through the valve but any which may escape around the stem is retained in the upper chamber until the pressure is reduced in the liquid chamber, whereupon the liquid trapped in the upper chamber will return by gravity to the liquid chamber through the check valve.

40 A further object is the provision of a door check so constructed as to be applicable either to double or single acting right or left hand doors; which shall have the smallest possible number of moving parts; which shall permit the ready opening of the door and a graduated closing.

45 These objects are secured in my check, in which is included a container provided with an oscillatory piston.

By my improvement a door check and closer may be formed of exceedingly few parts, none of which are liable to become out of order, which may be constructed rigidly, may be readily adjusted as required and which may be manufactured economically.

55 The invention will be more readily understood by reference to the accompanying drawings, wherein,

Figure 1 is a plan view of a door check and closer constructed in accordance with my invention; Fig. 2 is a longitudinal sectional view on the line 2—2 of Fig. 1; Fig. 3 is a transverse vertical section on the line 3—3 of Fig. 1; Fig. 4 is a section on the line 4—4 of Fig. 3; Fig. 5 is an enlarged perspective of the stem and wing piston secured thereto, and, Fig. 6 is a vertical section on the line 6—6 of Fig. 4.

Referring more particularly to the drawings it will be seen that I provide a casing member having a depending annular flange 10, threaded at its lower end, to which may be secured a bottom cap 11, having a hollow boss 12 therein, for the accommodation of the central shaft 13. The casing member is provided also with a lateral extension 14, in the form of a basin, this basin acting to contain suitable springs and also to act as a container for overflow or surplus liquid. This lateral member is suitably flanged to provide for the attachment of a top cover plate 15, by means of which the chamber is tightly closed. Suitably secured to the interior of the annular flange 10, is a metal plate 16, this plate acting as a wall, partially dividing the chamber into two compartments. This plate is rigidly secured to the casing member by means of screws 17. A regulating screw 18, is projected downwardly through the top wall and is provided with a transverse aperture 19 therein, the screw acting as a regulating device whereby the escape of liquid from one compartment to the other is controlled.

As best shown in Fig. 4, the wall 16 closely abuts the central shaft 13, making a comparatively tight connection therebetween. Secured to the shaft 13 is the wing piston 20, the outer edge of which closely fits the interior of the chamber containing the controlling liquid. By the addition of this wing piston the chamber is divided into two compartments normally of equal capacity. As best shown in Figs. 5 and 6, the wing 20 is apertured transversely and radially, the transverse apertures accommodating ball containers 21, 22, which devices act as check valves. The radial recess 23, is closed by the adjoining wall of the container when the wing is in normal position as shown in Fig. 4. However, as the wing piston is swung to right or left, the recess 23 registers with an eccentric groove 24, thus providing for the entrance of liquid into the recess and the escape of the liquid through one of the check

valves 21, 22. Thus it will be seen that assuming the container to be full of liquid, a movement of the wing piston in a clockwise direction will tend to compress the liquid within the upper half of the chamber as viewed in Fig. 4, this liquid being unable to escape through the check valve 21. However, as the wing piston is moved, the recess 23 is brought into register with the eccentric groove 24, and liquid is allowed to escape through the groove and recess and out the check valve 22, into the opposite side of the chamber. As the movement of the piston continues the liquid is transferred from one chamber to the other until the limit of movement is reached. On the return of the piston to normal position the escape aperture is at once closed off due to the fact that pressure is transferred from the upper to the lower chamber whereby the check valve 22 prevents the return of the liquid, except such as may escape around the face of the piston. The return of the wing to normal position is therefore controlled by the escape of liquid through the aperture 19, shown in Fig. 2. This construction provides an extremely efficient device and in practice it has been found that the return of the piston to normal position may be accomplished very quickly but with uniform motion throughout its return of travel. Of course, the action when the piston is moved in a counter-clockwise direction is the opposite of that just described.

It will be understood that under extreme pressure some liquid may escape upward around the shaft or stem 13. Any such liquid will be retained in the upper portion of the casing member it being intended that this portion of the device shall act as a reserve supply chamber. It is, however, desirable that any such liquid should be returned to the control chamber as soon as the parts return to their normal position. I have therefore provided in the dividing wall between the two chambers a check valve 25, as best shown in Fig. 3, this valve being moved against its seat whenever there is pressure in the control chamber, thus preventing the escape of any liquid from the control chamber into the expansion chamber.

As stated, the springs for closing the door are also contained in the upper chamber. These springs act upon the stem through a pair of oppositely disposed arms 26, 27, suitably secured to the stem by means of a set bolt 28, and carrying anti-friction rollers 29, these rollers cooperating with a reciprocating yoke 30, the legs of which are fitted against the walls of the lateral extension 14. A pair of helical springs 31, bear against the yoke 30, tending to force the same toward the stem. To prevent possible displacement of the yoke member 30, I provide the stem with an outwardly projecting

flange 32, which flange enters a slot in the levers 26, 27 and a notch 33, in the stem 13. Thus the springs and the yoke are maintained in position without reliance on the cover plate 15. Obviously by the employment of the yoke member described, a parallel axial motion of the springs is assured thus avoiding any torsional strains therein. Obviously also, the parts may be readily dismantled by the removal of the set bolt 28, and the slight compression of the springs 31, to permit the removal of the flange 32 from the notch in the stem 13.

I claim:

1. In a check for swing doors, the combination of a casing providing a chamber, said casing having on its inner surface a pair of eccentric surfaces, said surfaces being separated by a concentric surface, a piston mounted within said chamber and valves within said piston, the width of said concentric surface being substantially the same as the width of said piston at the point of coincidence, substantially as described. 80

2. In a door check having a container for a liquid to afford a checking medium, an oscillating piston having a port therethrough, and means for covering one end of said port, said means being graduated so as to fully close said port in one position and 90 to gradually uncover the same as the piston moves from said position, and a valve for controlling the opposite end of the port, substantially as described. 95

3. In a device of the class described, the combination of a container having a transverse interior wall, a wing piston rotatably mounted within said container, the inner face of said container being provided with an eccentric groove, said groove coöperating with said wing, and valves carried by said wing, substantially as described. 100

4. In a device of the class described, the combination of a container having a transverse inner wall, a wing mounted for oscillation within said container, said wing being provided with a recess having a port controlled by a valve, and an eccentric portion on the interior of said container, said portion coöperating with the recess in said wing whereby the passage of fluid through and around said wing is controlled, substantially as described. 110

5. In a device of the class described, the combination of a container having imperforate bottom and side walls, a piston mounted within said container, a closure for said container, said closure being provided with an over-flow chamber, and with a valved opening communicating with said container whereby fluid within said upper chamber may return to said container, substantially as described. 120

6. In a check and closer for double-acting doors, the combination of a liquid container, 125

a stem carrying a wing mounted for oscillation in the container, oppositely arranged check valves in said wing, said container having an eccentric portion arranged to co-operate with said wing whereby the passage of liquid around and through said wing is controlled, substantially as described.

7. In a door check, a container provided with an eccentric wall, a wing piston rotatably mounted in said container, said wing being provided with a radial recess, valved ports communicating with said recess, one end of said recess being adapted to be closed by said eccentric wall in one position of said wing and to be gradually opened by the movement of said wing relative to said eccentric wall, substantially as described.

8. In a device of the class described, the combination of a container having a transverse inner wall, a wing piston mounted for oscillation within said container, said piston having a valved port, and a concentric portion on the wall of said container at the point of rest of said piston and adapted to co-operate with said piston to interrupt the passage of fluid through and around said piston in one direction of movement of the piston, said valved port permitting the passage of liquid in another direction of move-

ment of the piston, substantially as described.

9. In a check for swing doors, the combination of a casing providing upper and lower chambers, a piston mounted in said lower chamber, the piston stem projecting upwardly through the walls separating said two chambers, and a check valve connecting said upper and lower chamber, said valve being adapted to be seated upwardly and to permit the passage of liquid from said upper chamber into said lower chamber in the absence of pressure in said lower chamber, substantially as described.

10. In a check for swing doors, the combination of a casing providing upper and lower chambers, a piston mounted in said lower chamber, springs mounted in said upper chamber and acting with said piston to control a swing door, and a check valve connecting said upper and lower chambers, said valve being adapted to permit the passage of liquid from said upper chamber to said lower chamber, substantially as described.
